UNITED STATES PATENT OFFICE.

HARRY E. O'REILLY, OF CHICAGO, ILLINOIS.

TOY.

Application filed July 14, 1924. Serial No. 725,986.

To all whom it may concern:

Be it known that I, HARRY E. O'REILLY, a citizen of the United States, residing at Chicago, in the county of Cook and State 5 of Illinois, have invented new and useful Improvements in Toys, of which the following is a specification.

This invention relates to toys and more particularly to a miniature loop-the-loop 10 for use in connection with a small weighted automobile or other wheeled vehicle.

An important aim of this invention is to provide a loop-the-loop which is entirely self-setting so that the only operation which 15 the user must perform is to place the miniature vehicle at the starting point after each trip.

A further object of the invention is to provide a toy of the character specified 20 wherein a novel form of latch is provided to secure a tiltable intermediate section in position to guide the vehicle onto the loop section whereby to cause the miniature vehicle to describe a practically complete 25 circle on each trip.

Also, an important aim of this invention is to provide a toy of the character specified which is of highly simplified construction, durable and cheap to manufacture.

30 Other objects and advantages will be apparent during the course of the following description. In the accompanying drawing forming a part of this application and in which like numerals are employed to designate like parts throughout the same.

Figure 1 is a side elevation of the improved toy;

Fig. 2 is a detail sectional view taken on line 2—2 of Fig. 1;

40 Fig. 3 is a detail sectional view illustrating the several positions which may be assumed by the intermediate and final or terminal section.

In the drawing, wherein for the purpose 45 of illustration is shown a preferred embodiment of the invention, the numeral 5 designates a base upon which the toy is mounted and the numeral 6 designates a standard of channeled or other formation and which acts 50 as a supporting means for a chute 7.

Fig. 3 illustrates that the chute 7 is of channel-shaped formation to guide the miniature weighted motor vehicle 8. In carrying out the invention the upper portion 55 of the chute 7 is curved longitudinally to provide a starting point for the motor ve-

hicle and the lower portion of the chute is provided with a rather slight longitudinal bend to direct the miniature vehicle onto an intermediate tiltable section generally 60 designated by the numeral 9. The tiltable intermediate section 9 is channel-shaped in cross-section and is provided with depending sides or ears 10 connected to a pivot pin 11. The pivot 11 is in turn connected to 65 the ears of a U-shaped supporting member 12 which may be mounted upon the base 5 as illustrated in Figs. 1 and 3.

As illustrated in Fig. 3, the lower portion of the chute 7 is provided with a short offset extension 14 which is overlapped by the adjacent portion of the tiltable intermediate section 9 whereby to provide a flat surface over which the miniature vehicle may travel. The tiltable section 9 is normally held in 70 contact with the extension 14 of the main chute by means of a latch 16 carried by a sheath 17. The sheath 17 is in turn carried by a U-shaped member 18 secured by rivets or otherwise to a pair of inclined supporting members 19 and 19' for a loop 20. The latch 16 is urged to its advanced position 75 in engagement with the section 9 by means of a spring 24 carried by an ear or wing 26 of an extension of the U-shaped member 80 18 which carries the ears 18.

The spring 24 is extended through the rear portion of the latch 16 and through the bottom of the loop 20 so that when the miniature vehicle enters the loop 20 it will engage the spring 24 and thereby move the latch 16 longitudinally so as to release the latch from engagement with the extended 90 end of the tiltable intermediate section 9.

As soon as the tiltable section 9 is released by the latch 16 a second spring 29 95 mounted on the pivot element 11 swings the section 9 to the dotted line position illustrated in Fig. 3.

When the tiltable section 9 is swung to 100 the position illustrated in dotted lines in Fig. 3 it is engaged with the discharge end of the loop 20 so as to receive the miniature vehicle when it is discharged from the loop.

When the spring 29 swings the tiltable 105 section 9 to the dotted line position illustrated in Fig. 3, a landing or final section 35 is swung from the full to the dotted line position illustrated in Fig. 3. The landing section 35 is in the nature of a lever 110 having ears 36 pivoted to the inclined braces 19 so that the same may move about a hori-

zontal axis. One end of the landing section 35 is provided with an extension 38 which is engaged by the under side of the intermediate section 9 so that when the adjacent end of the intermediate section is 5 swung downwardly the landing section will be swung upon its fulcrum, all of which is illustrated in full and dotted lines in Fig. 3.

10 As the vehicle travels along the landing section 35 it encounters a return bend 41 and the vehicle is immediately brought to a stop in the inclined position as shown in Fig. 3. When the vehicle reaches the return 15 bend 41 it swings the landing section 35 upon its fulcrum so that the same now assumes the position illustrated in full lines in Fig. 3. When the landing section is thus returned to the position illustrated in full 20 lines in Fig. 3, the intermediate section 9 will also be swung to its full line position and re-engaged by the latch 16 so that it is held in engagement with the chute 7 for receiving the vehicle 8 when it is again 25 started down the chute 7.

A toy constructed in accordance with this invention is unusually strong as the base 5 is preferably of channeled metal and the standard 6 which supports the chute 7 may 30 be riveted or otherwise secured to the chute 7 and to the base. The supports or inclined standards 19 and 19^a for the loop 20 firmly support the loop in its proper position and it will be seen that the inclined members 19^a 35 of which there may be two also firmly support the lower end of the chute 7.

Having thus described the invention, what is claimed is:

1. A toy of the character specified comprising a base, a chute arranged above the base, a tiltable section arranged at the lower end of the chute and having an extension overlapping the chute, and a loop arranged 40 at one end of the tiltable section.

45 2. A toy of the character specified comprising a base, a chute arranged above the base, a tiltable section arranged at the lower end of the chute and having an extension overlapping the chute, a loop arranged at one end of the tiltable section, and a latch carried by the loop and adapted to engage 50 said tiltable section to hold the same in position.

55 3. A toy of the character specified comprising a base, a chute arranged above the base, a tiltable section arranged at the lower end of the chute and having an extension overlapping the chute, a loop arranged at one end of the tiltable section, a latch carried by the loop and adapted to engage 60 said tiltable section to hold the same in position, and a spring connected to said latch and being movable through said loop.

65 4. A toy of the character specified comprising a base, a chute arranged above the

base, a tiltable section arranged at the lower end of the chute and having an extension overlapping the chute, a loop arranged at one end of the tiltable section, a latch carried by the loop and adapted to engage 70 said tiltable section to hold the same in position, a spring connected to said latch and being movable through said loop, and a spring urging 75 said tiltable section into engagement with the discharge end of said loop.

5. A toy of the character specified comprising a base, a chute arranged above the base, a tiltable section arranged at the lower end of the chute and having an extension overlapping the chute, a loop arranged at one end of the tiltable section, a latch carried by the loop and adapted to engage 80 said tiltable section to hold the same in position, a spring connected to said latch and being movable through said loop, a spring urging 85 said tiltable section into engagement with the discharge end of said loop, and a landing section fulcrumed at a point spaced from the center thereof and engaged with said tiltable section, the outer portion of the landing section being provided with a return bend.

6. A toy of the character specified comprising a base, a chute arranged above the base, a tiltable section arranged at the lower end of the chute and having an extension overlapping the chute, a loop arranged at one end of the tiltable section, a latch carried by the loop and adapted to engage 90 said tiltable section to hold the same in position, a spring connected to said latch and being movable through said loop, a spring urging 95 said tiltable section into engagement with the discharge end of said loop, a landing section fulcrumed at a point spaced from the center thereof and engaged with said tiltable section, the outer portion of the landing section being provided with a return bend, and a miniature vehicle adapted 100 to actuate the spring of said latch whereby 105 to cause said tiltable section to swing into engagement with the discharge end of said loop and to swing the landing section upon its fulcrum, said miniature vehicle being adapted to engage said return bend and to 110 return the tiltable section to a position in engagement with said chute.

7. A toy of the character specified comprising a base, a chute arranged above the base, a tiltable section arranged at the lower end of the chute and having an extension overlapping the chute, a loop arranged at one end of the tiltable section, a latch carried by the loop and adapted to engage 115 said tiltable section to hold the same in position, a spring connected to said latch and being movable through said loop, a spring urging 120 said tiltable section into engagement with the discharge end of said loop, a landing section fulcrumed at a point spaced from 125

the center thereof and engaged with said fulcrum, said miniature vehicle being adapted to engage said return bend and to return the tilttable section to a position in engagement with said chute, and supports for said loop, said chute, and said landing section.

In testimony whereof I affix my signature.

HARRY E. O'REILLY.
